INVENTOR.
JOSEPH W. BRENKERT.
BY *A. B. Bowman*
ATTORNEY

UNITED STATES PATENT OFFICE.

JOSEPH W. BRENKERT, OF SAN DIEGO, CALIFORNIA.

STREET-TRAFFIC-DIRECTION-SIGNALING DEVICE.

1,394,966.

Specification of Letters Patent.

Patented Oct. 25, 1921.

Application filed March 27, 1920. Serial No. 369,218.

To all whom it may concern:

Be it known that I, JOSEPH W. BRENKERT, a citizen of the United States, residing at San Diego, in the county of San Diego and State 5 of California, have invented certain new and useful Improvements in Street-Traffic-Direction-Signaling Devices, of which the following is a specification.

My invention relates to a street crossing 10 traffic signaling mechanism for indicating the direction the traffic will take at street crossings in congested districts in cities and the objects of my invention are: first, to provide a traffic signaling device to be operated 15 by a traffic officer for indicating the direction of traffic at crossings; second, to provide a device of this class which is actuated by the foot of the operator for revolving an indicating arm for indicating the direction 20 of traffic; third, to provide a device of this class which is easily operated and will maintain its position until reversed by the operator; fourth, to provide a device of this class 25 which is light and portable and may be readily carried to the place of operation by the operator and fifth, to provide a device of this class which is very simple and economical of construction, durable, easy to operate and which will not readily deteriorate 30 or get out of order.

With these and other objects in view as will appear hereinafter my invention consists of certain novel features of construction, combination and arrangement of parts 35 and portions as will be hereinafter described in detail and particularly set forth in the appended claims reference being had to the accompanying drawings and to the characters of reference thereon which form a part 40 of this application in which:

Figure 1 is a side elevational view of my device; Fig. 2 is a side elevational view at a right angle thereto showing a portion broken away and in section to facilitate the 45 illustration; Fig. 3 is a sectional view through 3—3 of Fig. 1 and Fig. 4 is a sectional view through 4—4 of Fig. 1 on an enlarged scale.

Similar characters of reference refer to 50 similar parts and portions throughout the several views of the drawings.

The base member 1, upright 2, support 3, levers 4 and 5, operating arm 6, revolute member 7, staff 8 and signal members 9 constitute the principal parts and portions of 55 my street traffic signaling device. The base

member 1 is provided with a lower flat surface for positioning on the street and is of sufficient size and weight to support the device in position. It is provided centrally 60 with an upright member 2 extending upwardly some distance and on the front side is provided with a reinforced boss 2^a and revolutely mounted therein is shaft 2^b which is provided with a partial ball member 2^c. Pivotedly mounted on this ball member 2^c is the operating arm 6 which extends upwardly some distance and is provided on its upper end with a weight 6^a. Pivotedly mounted on the shaft 2^b are the levers 4 and 5 which are bell crank members provided with offset portions adapted to engage the arm 6 and with offset members 4^a and 5^a adapted for engagement by the foot of the operator for operating said levers. 75

It will be here noted that these levers 4 and 5 are so constructed and positioned that their upright portions are engaged by the arm 6 only when the arm 6 has passed its perpendicular position in moving the traffic 80 signal and that the weight 6^a functions for shifting the signal after it passes this perpendicular position and it is raised to this perpendicular position by the operator by pressure on the foot levers 4 or 5. Mounted 85 on the base 1, back of the upright 2, is a support 3 which is provided with a right angled turn at its upper end and with a vertical bearing in the upper end forming a journal for the member 7 which is revolutely 90 mounted therein. This member 7 is provided with a ball race 7^a in its lower side filled with balls thus providing a ball bearing between the member 7 and the upright member 2. This member 7 is provided with 95 a side projecting slotted portion 7^b shaped as shown best in Fig. 3 of the drawings and through which the upper end of the arm member 6 extends so that when the arm member 6 is moved in either direction past 100 its upright position it engages the ends of the slots 7^b and turns the member 7 on the upright portion 2. This member 7 is also provided with outwardly projecting lugs 7^c which are adapted to engage the support 3 105 when revolved a certain distance thus forming a stop for the revolution of the member 7 at certain predetermined positions. The upper end of the member 7 is provided with a socket with a key way in one side thereof 110 and in which is mounted the staff 8 which is provided with a key adapted to engage

said key way for preventing the turning of the staff 8 relatively to the member 7. This staff 8 extends upwardly a suitable distance and on its upper end is provided a 5 signal member 9 which may be any form desired. It is preferred, however, to have four extended portions which may have characters printed thereon for indicating whether the traffic shall proceed or stop.

10 Though I have shown and described a particular construction, combination and arrangement of parts and portions I do not wish to be limited to this particular construction, combination, and arrangement but 15 desire to include in the purview of my invention the construction, combination and arrangement substantially as set forth in the appended claims.

It is obvious that with this construction, 20 there is provided a device for signaling the movement of the traffic at street crossings which may be operated by a traffic officer which eliminates the necessity of said officer holding his arms in position for indicating 25 the direction of traffic and which is easily operated by the foot levers 4 and 5 by shifting the arm 6 past center after which the weight 6^a revolves the member 7, staff 8 and signals 9 to the proper position and is 30 stopped by the lugs 7^c engaging the member 3.

Having thus described my invention what I claim as new and desire to secure by Letters Patent is:

35 1. A street crossing traffic direction signal, including a base member, a staff revolvably mounted thereon, provided with a laterally extending side portion, an over center weighted arm pivotally mounted on said 40 base member adapted to engage said side

portion, operated by the traffic officer for revolving said staff, means for stopping its revolution at a certain pre-determined point and a traffic signal member secured on the upper end of said staff. 45

2. A street crossing traffic direction signal, including a base member, a staff revolvably mounted thereon, provided with a laterally extending side portion, a weighted arm pivotally mounted on said base member extending upwardly adapted to swing on its pivotal mounting for engaging said side portion when swung in opposite direction on its pivotal mounting, foot operated means for swinging said weighted arm on its pivotal mounting, means for stopping its revolution at a certain pre-determined point, and a traffic signal member secured on the upper end of said staff. 50 55

3. A device of the class described, including a base member provided with a central upright portion, an arm pivotally mounted thereon extended upwardly, a pair of foot levers engaging the opposite side of said arm for shifting the same, another arm secured 60 to said base extending upwardly forming a journal member, a member revolvably mounted in said journal member and revolvably supported on said central upright support and provided with an extended slotted member 65 through which the upper end of said arm passes, a staff secured in the upper end of said revolvable member provided with means for preventing its turning in said revolvable member and a traffic signal secured on the 70 upper end of said staff. 75

In testimony whereof I have hereunto set my hand at San Diego, California, this 19th day of March, 1920.

JOSEPH W. BRENKERT.
